Joseph Ingels
By attorney A. B. Stoughton.

United States Patent Office.

JOSEPH INGELS, OF MILTON, INDIANA.

Letters Patent No. 102,940, dated May 10, 1870.

IMPROVEMENT IN DOUBLE AND SINGLE-TREE FASTENINGS FOR CARRIAGES.

The Schedule referred to in these Letters Patent and making part of the same

To all whom it may concern:

Be it known that I, JOSEPH INGELS, of Milton, in the county of Wayne and State of Indiana, have invented certain new and useful Improvements in Double and Single-tree and Neck-yoke Connections for Carriages; and I do hereby declare that the following is a full, clear, and exact description of the construction and operation of the same, reference being had to the accompanying drawings making a part of this specification, in which—

Figure 1 represents, in perspective, a portion of a carriage tongue, double and single-tree, and a trace, and the manner of uniting them one to the other;

Figure 2 represents a longitudinal section through the same;

Figure 3 represents, in perspective, a portion of the point of the pole with the neck-yoke united thereto; and

Figures 4 and 5 represent detached portions, that will be hereafter more particularly referred to.

Similar letters of reference, where they occur in the several separate drawings, describe like parts of the contrivances in all of the figures.

My invention relates—

First, to certain devices for making a strong, yet freely moving connection between the double-tree and the pole of a carriage, and between the single and the double-tree; and

Secondly, it relates to the fastening by which the traces are secured to the single-tree, as also the yoke is secured to the end of the pole, so that they may hold firmly, yet be readily detached or unfastened.

To enable others skilled in the art to make and use my invention, I will proceed to describe the same with reference to the drawings.

A split cup or socket, *a*, is let into the pole *A*, and bolted thereto as at *b*.

This cup has a flange at its upper end, which bends or curves over as at *c*, so as to take over and hold upon the flange *e* of an inverted cup or socket, *d*, partially let into the double-tree *B*, and bolted thereto by the bolt *f*.

The socket or cup *d* need not be divided, as the under divided one, *a*, admits of putting the flanges of the two together.

In these sockets or cups, so as to extend into each and break the joint between them, is placed a plug, *C*, around which one or both of the cups or sockets may freely move, as well as move on each other at their flanged connection.

The plug *C* is loose in the cups, but it might be attached to, or be the head of, one of the bolts *b f*, and have the same strengthening effect, but in that case, could only turn with either the pole or the double-tree.

The single-trees *D* I propose to unite to the double-tree *B* in the same manner, and need not be specially described, as it is clearly shown in the drawing, and by the same letters of reference.

The trace-holder *E* I make of a hollow spherical, or nearly so, head, and a socket to receive the end of the wood.

This head is slotted, as at *g*, and cut away, as at *h*, so that the button *i* on the trace-fastener *F*, fig. 5, may pass into the opening *h*, and its shank portion *j* move through the slot *g* until it comes into the position shown in fig. 1, when the trace is securely attached to the single-tree, and can only be detached by reversing the operation, and carrying the button *i* clear back to the opening *h* before it can pass out.

The trace *G* is fastened to the trace-iron, hook, or button *F* by a stud, *k*.

The neck-yoke *H* is fastened or secured to the end of the pole *A*, fig. 3, by a device substantially like that which holds the trace to the singletree, viz: a slotted, hollow, and under-cut head, *I*, into which a button, *m*, on the shank *n*, enters underneath, and swings around and upward, the opposite end of the shank or coupling having on it another button, *o*, which holds in the strap or neck-yoke iron *p*.

A section of the divided socket, or one-half of it, is shown in perspective at fig. 4, and marked by the letter *a*.

Having thus fully described my invention, What I claim is—

A single or double-tree fastening, composed of the hollow sockets, one of which is split, the plug and bolts, substantially as and for the purpose described.

Also, a brace or neck-yoke fastening, composed of the hollow, slotted, and cut-away head and a shank, having a button at each end, one to hold itself to the trace or neck-yoke, and the other fasten the trace to the single-tree, or the neck-yoke to the pole, substantially as described.

JOSEPH INGELS.
